UNITED STATES PATENT OFFICE.

GEORGE W. RAMER, OF DAVIS CREEK, CALIFORNIA.

RELEASING-PENHOLDER.

1,239,126.

Specification of Letters Patent.

Patented Sept. 4, 1917.

Application filed January 9, 1917. Serial No. 141,410.

To all whom it may concern:

Be it known that I, GEORGE W. RAMER, a citizen of the United States, residing at Davis Creek, in the county of Modoc and State of California, have invented certain new and useful Improvements in Releasing-Penholders, of which the following is a specification.

This invention relates to an improved type of releasing pen holder and the primary object is to provide a device for permitting the ejection of a defective or worn-out pen point from the end of the holder without the necessity of grasping the same by the fingers of the person using the device.

A further object of the invention is the provision of a device of this character that will permit the easy ejection of a pen point without the necessity of touching the pen point.

The invention also aims to provide a device of this character which will have but a single movable part that may be associated with the ordinary pen holder of well-known design by merely making a slight change in the construction thereof.

A further object of this invention is the provision of a releasing pen holder which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawing, wherein is illustrated the preferred form of my invention, in which:

40 Figure 1 is a top plan view.

Fig. 2 is a longitudinal section.

Fig. 3 is a transverse section on the line 3—3 of Fig. 2.

Fig. 4 is a transverse section on the line 45 4—4 of Fig. 2.

Fig. 5 is a longitudinal section showing the device in position for ejecting a pen point, and

Fig. 6 is a fragmentary longitudinal section of a slightly modified form.

Referring to the drawing, wherein is illustrated the preferred form of my invention, and in which like numerals of reference indicate corresponding parts throughout the several views, the handle 1 carries a metallic ferrule 2 in the usual manner. Within the

open end of the ferrule is a sleeve 3 formed by an inwardly bent cylindrically shaped portion of the end of the ferrule. Between the inner wall of the ferrule and the outer 60 wall of the sleeve 3 the pen point 4 is received in the usual manner. A relatively wide slot 5 is provided in the ferrule 2 and this slot opens at the end of the ferrule and is flared outwardly to increase its width as 65 clearly shown by Fig. 1 of the drawing. It is obvious, that this slot 5, together with the assistance of the slit 6 from which the inner sleeve 3 is bent will permit the end of the ferrule to possess sufficient resiliency whereby it 70 may be slightly spread outwardly when desired. Arranged within the ferrule is a clip 7 which is curved transversely to conform to the curve of the ferrule 2 and the length of the clip is slightly greater than the length 75 of the slot 5. The forward end of the clip is tapered and slightly turned upwardly to provide a finger 8 by which the clip may be lifted when operating for releasing the pen point 4. The width of the clip is slightly 80 greater than the width of the slot 5 thereby permitting the edges of the slot to overlap the edges of the clip.

A pen point will be inserted between the sleeve 3 and the clip 7 as clearly shown by 85 Figs. 2 and 4 of the drawing. It is obvious, that merely, the overlapping edges of the slot 5 will hold the clip 7 in engagement with the pen point so that the pen point will be rigidly held against accidental 90 displacement while being used. When it is desired to eject the pen point, however, it is merely necessary for the operator to place his finger beneath the upturned finger 8 and lift the clip 7, the same pivoting on the 95 pivot pin 9 provided for this purpose. This lifting action will cause the edges of the tapered end of the clip to force the edges of the slot slightly apart due to the resiliency above described. The pen point may then 100 easily drop out as shown by Fig. 5 of the drawing and if the pen point is corroded, it is merely necessary to strike the same against the edge of a waste basket or other convenient receptacle and the pen point will 105 immediately drop out of place. As soon as the clip 7 has been released, it will snap back into place where it will be ready to receive a new pen point.

As shown by Fig. 6 of the drawing the 110 clip 7 is mounted in place without the use of the pivot pin 9 mentioned in the above

described form. In this instance, the upturned end 8' will be lifted and pulled slightly rearwardly until the clip is disengaged from the pen point 4' thereby permitting the same to be ejected.

From the foregoing it will be observed that a very simple and durable releasing pen holder has been provided, the details of which embody the preferred form. I desire it to be understood however, that slight changes in the minor details of construction may be made without departing from the spirit of the invention or the scope of the claims hereunto appended.

15 I claim:

1. In a releasing pen holder, the combination with a handle having a ferrule attached to one end thereof and provided with a slot communicating with the free end of the ferrule, and means arranged within the ferrule and adapted to be manually operated for causing the side edges of the slot to be spread apart whereby the pen may be permitted to drop from its position in the 25 end of the said ferrule.

2. In a releasing pen holder the combination with a handle having a ferrule mounted on one end and provided with a slot extending inwardly from the free end of the ferrule, the end of the slot being slightly flared outwardly at the end of the ferrule, and means pivotally movable within the ferrule and engageable with the edges of the said slot for causing the end of the ferrule to 35 spread outwardly whereby the pen may be released from the end of the ferrule.

3. In a releasing pen holder, the combination with a handle having a ferrule mounted on one end, the ferrule also having a slot, 40 a sleeve arranged within the end of the ferrule and adapted to engage the end of a pen point embraced by the end of the said ferrule and a clip pivotally associated with the ferrule and normally held in engagement

with the end of the pen point within the ferrule and movable in the said slot.

4. In a releasing pen holder, the combination with a handle having a ferrule mounted on one end, a sleeve arranged within the end of the ferrule and adapted to engage the end 50 of a pen point embraced by the end of the said ferrule, a clip pivotally associated with the ferrule and normally held in engagement with the end of the pen point within the ferrule, the said ferrule having a slot the edges 55 of which overlap the edges of the said clip whereby the end of the ferrule will be spread outwardly when the clip is raised through the said slot.

5. In a releasing pen holder, the combination with a handle having a ferrule mounted at one end, the ferrule being provided with a relatively wide slot extending from the open end of the ferrule and slightly flared outwardly at its open end, a sleeve arranged 65 within the end of the ferrule and adapted to engage a pen point embraced by the ferrule, and a clip slightly greater in width than the width of the said slot whereby the edges of the said slot will overlap the edges 70 of the said clip, the said clip being in engagement with the fixed end of the said pen point, and a finger formed at the end of the said clip.

6. A releasing pen holder comprising a 75 ferrule having a handle fixed to one end the said ferrule also having a slot, a clip pivotally mounted and of a width slightly greater than the width of the slot, the clip being mounted to be forced through the slot 80 to distort the open end of the ferrule when the clip is actuated.

In testimony whereof I affix my signature in presence of two witnesses.

GEORGE W. RAMER.
